CLAIM

The ornamental design for a surge protector, as shown and described.

DESCRIPTION

FIG. 1 is a pictorial view from the top, front and left of the surge protector;

FIG. 2 is a rear elevational view of the surge protector of FIG. 1;

FIG. 3 is a bottom plan view of the surge protector;

FIG. 4 is a right elevational view of the surge protector; and,

FIG. 5 is a pictorial view from the top, front and left of an alternative embodiment of the surge protector, the other three sides being similar to the corresponding sides of the surge protector of FIG. 1 as shown in FIGS. 2-4.
